Primary Examiner — Leanne Was-Englehart

(74) Attorney, Agent, or Firm — Kathleen Y. Carter

(57) **CLAIM**

The ornamental design for a Bottle, as shown and described.

DESCRIPTION

FIG. 1 is a perspective view of a bottle showing our new design;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof;

FIG. 8 is a front view of the bottle in an opened position, wherein the collar is rotated relative to the nozzle.
